UNITED STATES PATENT OFFICE.

HENRY H. VAUGHAN, OF MONTREAL, QUEBEC, CANADA.

SYSTEM OF HEAT GENERATION AND DISTRIBUTION FOR RAILWAY-CARS.

1,311,783.

Specification of Letters Patent. Patented July 29, 1919.

Application filed November 29, 1915. Serial No. 64,097.

To all whom it may concern:

Be it known that I, HENRY H. VAUGHAN, a citizen of the United States, residing at Montreal, in the Province of Quebec, Dominion of Canada, have invented certain new and useful Improvements in Systems of Heat Generation and Distribution for Railway-Cars, of which the following is a specification.

10 My invention relates to a system of heat generation and distribution, and the principal object of the invention is to provide an improved apparatus of this sort for use particularly in dining cars, private cars, 15 and the like, furnished with cooking devices, requiring a heating medium at certain times, as well as with radiators for heating the car during cold weather. The invention contemplates the employment, wherever possible, of steam taken from the steam train line, that is, from the supply pipe running the length of the train and receiving its supply of steam from the locomotive. Cars of the type mentioned are, however, likely 20 to stand disconnected from a locomotive for considerable periods of time, during which they may be occupied so as to require heating medium either for cooking or general heating purposes, or both. The invention, 25 therefore, provides, in its preferred embodiment, a closed hot water circulating system for keeping the car at a proper temperature during cold weather and a local steam generator, which may be used when train line 30 steam is not available, for generating steam for heating the water in the water circulatory system and also for supplying steam and water of condensation to the cooking devices.

35 The invention has for a further object to provide certain new and useful improvements in a steam generator for use in a system of the type above described or in analogous situations.

40 With the above stated objects in view, my invention consists in the novel and improved devices, arrangements and constructions in a heat generating and distributing system for railway cars which will be hereinafter 45 described and claimed.

The invention is illustrated, in certain preferred embodiments, in the accompanying drawings wherein—

Figure 1 is a diagrammatic representation 55 of a dining car furnished with a generating

and distributing system constructed according to the principles of my invention; the car being shown in plan section and certain parts of the heating system in plan and others in elevation.

60

Fig. 2 is a sectional elevation, on an enlarged scale, of the steam generator, the cooking devices and certain other related elements of the system.

Fig. 3 is a fragmentary, vertical sectional view of the upper portion of the generator.

Fig. 4 is a sectional plan on line 4—4 of Fig. 2.

Fig. 5 is a detail view, in elevation, of the lever for operating certain of the valves or 70 dampers of the generator.

Fig. 6 is a view, similar to Fig. 2, illustrating a modification.

Fig. 7 is a vertical sectional view illustrating the construction of one of the two pairs 75 of valves employed in the modified system shown in Fig. 6 for preventing circulation through the water circulatory system at such times as the car does not require artificial heating.

Fig. 8 is a sectional view taken on line 8—8 of Fig. 7, and

Fig. 9 is a view, similar to Fig. 6, illustrating another modification.

Like characters of reference designate 85 like parts in the several figures of the drawings.

Referring first to Figs. 1 to 5 inclusive, 10 designates a dining car of which 11 is the dining-room section and 12 the kitchen section. 13 is the steam train pipe which runs the length of the train and receives steam from the locomotive. 14, 14^a are water circulating coils or radiators, and 15, 15^a their respective expansion tanks. The 90 water for the water circulatory system, consisting of radiators 14, 14^a, is heated by means of steam taken from the train pipe 13, when steam is available from this source, or when not so available, by local steam generated by the steam generator 16. The steam heating device for heating the water in this manner consists preferably of water coils 17, 17^a through which extend steam coils 18, 18^a which are connected by pipes 19, 20 with 95 the train pipe 13 and by pipes 19, 21 with the steam space 22 in the boiler 23 of the generator. The generator is preferably formed with an inner flue 24 and an outer flue 25, and the duplex coils 17, 17^a, 18, 18^a 100 105 110

are located in the outer flue. Suitable valves or dampers are provided for the purpose of directing the gases of combustion from the fire box 26 of the generator into either 5 the inner flue or the outer flue. When the water circulatory system is in operation, that is, during winter weather, the heat from the generator passes to the stack flue 27 through the outer connecting flue 25, 10 and by coming into contact with the water coils 17, 17^a assists the steam in heating the water therein. In warm weather, when the system is used only for cooking purposes, the products of combustion are 15 excluded from the outer flue and from contact with the water heating coils and pass to the stack through the inner flue 24. With these ends in view, the annular member 28, which separates the outer flue 25 from the 20 inner flue 24, is provided with openings 29 adapted to be closed by a damper 30 manipulated by a handle 31 which extends through a slot 32 in the outer wall 33 of the upper portion of the generator. The inner flue is 25 provided at the bottom with a damper 34 carried on a rod 35 which extends through the cylindrical member 36 defining the inner flue and through the wall 33, and is provided with a handle 37 having a slight rocking movement to and from the wall of the 30 generator. The handle is pressed by a spring 38 and is formed with a tooth 39 adapted to engage with one or other of the openings 40 formed in a plate 41 on the side 35 of the generator. In telescopic relation with the upper end of the cylindrical member 36 is a sleeve 42 adapted to align with the stack flue 43 of the generator. The sleeve 42 is connected by a link 44 and cross piece 45 40 with the damper 34. When the damper 34 is open sleeve 42 is raised so as to shut off communication between the outer connecting flue 25 and the stack flue 43. When damper 34 is closed the sleeve 42 is lowered to a 45 position which will permit the gases of combustion to pass from the outer connecting flue 25 into flue 43. The cooking devices which, in the preferred arrangement shown, consist of a steam cooker 46, a cup warmer 47, a bain marie 48, a steam table 49, and a steam kettle 50, are heated by steam, and water of condensation, taken from the steam generator through pipe 19^a, which is a continuation of pipe 19, the steam passages of 55 the devices 46, 47, 48, 49, being connected together and the water of condensation from the steam table 49 being returned to the boiler 23 of the generator by pipe 51. The steam kettle 50 is connected to pipe 19^a by 60 a pipe 52 and discharges into pipe 51 through a pipe 53. The latter is provided with a check valve 54 which prevents pressure in the steam boiler from backing the water of condensation into the steam kettle above the 65 water level in the boiler. Pipe 51 is pro-

vided with a similar check valve 55. The steam coils of the water heating device 18, 18^a discharge into a pipe 56 which runs to pipe 51. A pipe 57 leads from pipe 56 to a steam trap 58 under the floor of the car. 70 Pipe 57 is connected with pipe 21 by a short pipe section 58^a. 59 is a water supply tank connected by a pipe 60, 60^a with pipe 51. A hand pump 61 is interposed between the pipe sections 60, 60^a. The latter taps pipe 75 51 at a point between a check valve 62 and the boiler. The boiler has the usual water gage 63 and steam pressure gage 64. Pipes 19, 20, 21, 19^a, 51, 57 and 60^a are provided with shutoff valves numbered respectively 80 65, 66, 67, 68, 69, 70 and 71.

The operation of the apparatus above described is as follows: When train pipe steam is available, valves 66 and 70 are opened and valves 67 and 69 closed. 85

If the car is to be heated (as in winter) steam flows from the train pipe 13 and pipe 20 through pipe 19, valve 65 being opened, and the steam coils 18, 18^a. Water of condensation is discharged through pipes 56, 57 90 and trap 58. If steam is required for the steam cooking devices 46, 47, 48, 49, 50 (which with their connecting conduits will be termed, somewhat arbitrarily, in certain of the claims, the steam circulatory system) 95 valve 68 is opened and steam from pipe 20 flows through pipe 19^a to the cooking devices, the water of condensation outflowing through pipes 51, 53, 56, and thence into pipe 57 leading to the trap. Certain of the 100 steam cooking devices, for example the devices 48, 49, 50, are heated in whole or in part by water of condensation. For this reason the pipe 57 taps pipe 56 at the water level of the system, that is to say, the normal water level in the boiler 23 of generator 105 16.

When the car is cut off from a train and train pipe steam is no longer obtainable, steam is generated in the generator by lighting a fire in the fire box 26. Under these conditions valves 66 and 70 are closed and valves 67, 69 opened. For heating the water in the radiators 14, 14^a, steam passes from the boiler 23 through pipes 21 to pipe 19 115 115 and thence through the steam coils 18, 18^a, water of condensation being returned to the boiler through pipes 56 and 51.

Steam for the cooking devices enters pipe 19^a from pipe 20. Water of condensation is 120 returned to the boiler through pipe 51.

Thus when operating with steam generated in the generator the system is a closed system, the water of condensation being saved and returned to the generator. When 125 operating with steam taken from the train pipe the water of condensation is discharged to the atmosphere. It might, of course, if desired, be returned to some suitable storage tank. In any event, it is discharged out of 130

the system. Water losses, which may occur when the system is operated as a closed system, may be replenished by operating pump 61. Check valve 62, in such case, prevents 5 water from being forced back into the cooking devices.

In the arrangement shown in Figs. 1 to 5 inclusive, the steam heating device, consisting of coils 17, 17^a, 18, 18^a, is located in a flue 10 or space 25 between the combustion chamber 26 of the generator and the stack flue 27 so that heat from the generator will come into contact with the water coils, thereby assisting the steam in heating the water in 15 said coils. In such case, damper 34 is closed and sleeve 42 lowered and damper 30 opened. When no artificial heat is required for the car the damper 34 is opened, damper 30 closed and sleeve 42 raised so that the products 20 of combustion pass through the inner flue 24 and do not heat the water coil.

This same result is obtained in a different way by the modified apparatus shown in Fig. 6. In this case the generator 72 has a 25 single flue or space 73 in which the duplex water coil 74 is located so that whenever fire is lighted in the generator the water in the coil 74 is necessarily heated. The water, however, is prevented from circulating 30 through the radiators, the connecting pipes of which are designated 75, 76 and 77, 78, by two pairs of valves, one pair for each radiator. These valves are the same for each radiator, the construction of one pair, 35 that for pipe 75, 76, being shown in Figs. 7 and 8. 79 is a valve casing interposed in pipe 75, and 79^a a similar casing interposed in pipe 76. The valve casings are connected by a pipe section 80. In the casings are 40 revolvable valve bodies 81, 81^a formed with ports 82, 82^a and branch ports 83, 83^a. The valve bodies are provided with handles 84. With the valves in the position shown in Fig. 7 the water heated in coils 74 will circulate 45 through the radiator connected with pipes 75, 76. With the valves turned at right angles to the position shown in Fig. 7, in the direction, in each case, indicated by the curved arrows outside the valve casings, 50 the water from the water coil 74 will pass from one valve through connecting pipe 80 to the other valve and back to the heating coil.

In other respects the system, so far as 55 shown in Fig. 6, is the same as that shown in the previous figures. The corresponding parts shown in Fig. 6 are designated by corresponding numerals.

A further modification is shown in Fig. 9. 60 The water heating coil 85 is arranged outside of the generator 86. It therefore receives comparatively little heat, the heating of the water being accomplished almost exclusively by the steam generated in 65 the generator. The arrangement, however,

has the advantage that the coil can be made larger in diameter and hence its vertical dimension may be diminished. It also may be arranged nearer the floor so that the water circulation from the coil to the expansion 70 tanks 87, 88 is increased whereby a quicker circulation through the radiators is obtained.

In this modification, the construction, except in the respects above described, is the 75 same as in the preceding figures so that the elements of the system shown but not described have been given the same reference numerals as the corresponding parts in the previously described construction. 80

While I have described my invention in certain preferred embodiments, it will be understood that further modifications might be made without departure from the principles of the invention. Therefore I do not 85 wish to be understood as limiting the invention to the precise constructions, arrangements and devices shown and described except so far as the claims are specifically so limited. 90

I claim:

1. In a heat generating and distributing apparatus for a railway car, the combination of a water circulating system, a steam generator having a fire box, boiler and two 95 flues; a steam circulatory system and a steam heating device for the water system adapted to receive steam from the boiler of the generator separately or conjointly; the heating device being arranged in one of the 100 flues of said generator; and means for directing gases of combustion from the fire box of the generator through either one or the other of said flues, as desired. 105

2. In a heat generating and distributing 110 apparatus for a railway car, the combination of a steam generator having a fire box, boiler and two flues; a closed water coil in one of said flues, a steam operated heating device for said coil in the same flue adapted 115 to receive steam from the boiler of said generator, and means for directing gases of combustion from the fire box of the generator through either one or other of said flues, as desired. 115

3. In a heat generating and distributing apparatus for a railway car, the combination of a steam generator, a steam operated water heating device adapted to receive steam from said generator, and means for 120 directing heat from the generator against the water heater or away from the same, as desired.

4. In a heat generating and distributing apparatus for a railway car, the combination 125 of a steam generator having a fire box, a boiler, an inner flue and an outer flue; means for directing gases of combustion into either the inner flue or the outer flue; and a duplex water heating coil in one of said 130

41

flues consisting of a water pipe and within the same a steam pipe, the latter being connected with the boiler of the generator.

5. In a heat generating and distributing apparatus for a railway car, the combination of a steam generator having a fire box, a boiler, an inner flue and an outer flue; means for directing gases of combustion into either the inner flue or the outer flue; and a 10 duplex water heating coil in the outer flue consisting of a water pipe and, within the same, a steam pipe, the latter being connected with the boiler of the generator.

6. In a heat generating and distributing apparatus for a railway car, the combination of a steam generator having a fire box, a boiler, an inner flue, an outer flue, and a 15 stack flue which latter extends through the roof of the car; means for putting either the inner or outer flue in communication with the fire box and the stack flue and excluding gases of combustion from the other of said first named flues; and a duplex water heating coil in the outside flue consisting of a 20 water pipe and within the same a steam pipe which is connected with the boiler of the generator.

7. In a heat generating and distributing apparatus for a railway car, the combination of a steam generator comprising a fire box, a boiler, inner and outer flues, and a stack flue, a damper in the bottom of the inner flue, a sleeve at the upper end of the inner flue connected with said damper so as to be 30 raised and lowered to put the inner and outer flues respectively, in communication with the stack flues, a damper to control the flow of gases from the combustion chamber to the outer flue, and a duplex water heating coil in the outer flue consisting of a water pipe, and a steam pipe within the water pipe which is connected with the 35 boiler of the generator.

8. In a heat generating and distributing apparatus for a railway car, the combination of a steam generator having a fire box, a boiler and a flue, a duplex water heating coil arranged in said flue comprising a water pipe and a steam pipe within the water pipe 40 which is connected with the boiler of said generator.

9. In a heat generating and distributing apparatus for a railway car, the combination of a steam train pipe, a hot water circulatory system, a steam generator, a steam circulatory system adapted to receive steam either from the generator or the train pipe, and a steam heating device for the water system adapted to receive steam from the 50 generator or the train pipe and arranged so as to receive heat directly from the generator.

10. In a heat generating and distributing apparatus for a railway car, the combination of a steam train pipe, a hot water circulatory 55

system, a steam generator, a steam circulatory system adapted to receive steam either from the generator or the train pipe, and a steam heating device for the water system adapted to receive steam from the 60 generator or the train pipe and arranged so that heat from the generator may be directed against the same or away from the same, as desired.

11. In a heat generating and distributing apparatus for a railway car, the combination of a train pipe, a steam generator, and a steam operated water heating device arranged so as to receive heat directly from the 65 generator and to be supplied additionally with steam therefrom or from said train pipe.

12. The combination with a railway car, of a steam train pipe, a hot water radiator in the car, a steam cooking apparatus in 70 the car, a steam operated device for heating water for the water radiator, a steam generator, means for supplying steam to said heating device and cooking apparatus from either the train pipe or the steam 75 generator, a return pipe for returning water of condensation to the boiler of the generator when the latter is in operation, a steam trap for discharging water of condensation when steam is taken from the 80 train pipe, and a pipe leading to the trap which taps said return pipe at the normal water level of the boiler of the generator.

13. The combination with a railway car and steam train pipe, of the following instrumentalities located in the car, namely, a water circulatory system, a local steam generator, a heating device for heating the water of the water circulatory system which employs steam as its heating medium, means 100 whereby steam may be supplied to said heating device either from the local steam generator or from the train pipe, as desired, a discharge device for water of condensation from the heating device, and means whereby said water of condensation may be returned to the boiler of the local steam generator or discharged through said discharge device.

14. The combination with a railway car and steam train pipe, of the following instrumentalities located in the car, namely, a water circulatory system, a local steam generator, a heating device for heating the water of the water circulatory system which 110 employs steam as its heating medium, a separate steam circulatory system, and means whereby steam may be supplied to said heating device or to said steam circulatory system, or to either of them, either 115 from the local steam generator or from the train pipe, as desired.

15. The combination with a railway car and steam train pipe, of a water circulatory system in the car, a local steam generator, 120

a heating device for heating the water of the water circulatory system which employs steam as its heating medium, a separate steam circulatory system, and means whereby steam may be supplied to said heating device or to said steam circulatory system, or to either of them, either from the local steam generator or from the train pipe, as desired, a discharge device for water of condensation from said heating device and steam circulatory system, or either of them, and means whereby said water of condensation may be returned to the boiler of the local steam generator or discharged through said discharge device.

16. The combination with a railway car and steam train pipe, of a water circulatory system in the car, a local steam generator, a heating device for heating the water of the water circulatory system which employs steam as its heating medium, a separate steam circulatory system, means whereby steam may be supplied to said heating device or to said steam circulatory system, or either of them, either from the steam generator or from the train pipe, as desired, and means for maintaining water of condensation at a constant level in said separate steam circulatory system.

17. The combination with a railway car and steam train pipe, of a water circulatory system in the car, a local steam generator, a heating device for heating the water of the water circulatory system which employs steam as its heating medium, means whereby steam may be supplied to said heating device either from the local steam generator or from the train pipe, as desired, said heating device being located so that it may be heated directly by the fire in said generator, and means whereby the heat from the local steam generator fire may be deflected from said heating device so that it does not come into direct contact therewith.

18. The combination with a railway car and steam train pipe, of a closed water circulatory system comprising radiating pipes and a coil in which the water is heated, a local steam generator comprising a firebox and a boiler, the latter providing a space for water and steam, steam cooking apparatus, a steam coil for heating the water in said water coil, pipe connections having shut-off valves whereby steam may be supplied to the steam coil or to the cooking apparatus or to both from either the local steam generator or from the train pipe, a discharge device for water of condensation and pipe connections having shut-off valves whereby water of condensation from the steam coil or steam cooking apparatus can be either returned to the boiler of the local steam generator or discharged through said discharge device.

19. The combination with a railway car and steam train pipe, of a closed water cir-

culatory system comprising radiating pipes and a coil in which the water is heated, a local steam generator comprising a fire-box and a boiler, the latter providing a space for water and steam, steam cooking apparatus 70 arranged so that a part of the same is below the normal water level in the boiler of the local steam generator, a steam coil for heating the water in said water coil, pipe connections having shut-off valves whereby 75 steam may be supplied to the steam coil or to the cooking apparatus or to both from either the local steam generator or from the train pipe, a discharge device for water of condensation and pipe connections having 80 shut-off valves whereby water of condensation from the steam coil or steam cooking apparatus can be either returned to the boiler of the local steam generator or discharged through said discharge device, said 85 discharge device being arranged to receive water of condensation at a level substantially that of the water level in the boiler so that water is maintained at a constant level in the cooking apparatus whether such apparatus be supplied from the train pipe or from the local steam generator.

20. The combination with a railway car and steam train pipe, of a closed water circulatory system comprising radiating pipes and 95 a coil in which the water is heated, a local steam generator comprising a fire-box and a boiler, the latter providing a space for water and steam, steam cooking apparatus, a steam coil for heating the water in said water coil, 100 pipe connections having shut-off valves whereby steam may be supplied to the steam coil or to the cooking apparatus or to both from either the local steam generator or from the train pipe, a discharge device for 105 water of condensation and pipe connections having shut-off valves whereby water of condensation from the steam coil or steam cooking apparatus can be either returned to the boiler of the local steam generator or discharged through said discharge device; said water coil being located within the local steam generator so that it may receive heat directly therefrom as well as from the steam generated thereby.

21. The combination with a railway car and steam train pipe, of a closed water circulatory system comprising radiating pipes and a coil in which the water is heated, a local steam generator comprising a fire-box 120 and a boiler, the latter providing a space for water and steam, steam cooking apparatus, a steam coil for heating the water in said water coil, pipe connections having shut-off valves whereby steam may be supplied to the 125 steam coil or to the cooking apparatus or to both from either the local steam generator or from the train pipe, a discharge device for water of condensation, pipe connections having shut-off valves whereby water of condensation from the steam coil or steam cooking apparatus can be either returned to the 130 boiler of the local steam generator or discharged through said discharge device.

densation from the steam coil or steam cooking apparatus can be either returned to the boiler of the local steam generator or discharged through said discharge device, a water supply tank, a pump for forcing water therefrom into the water space of the local generator, and a check valve to prevent

water from being forced backwardly into the cooking apparatus.
